UNITED STATES PATENT OFFICE

RALPH E. HELLMER, OF PHILADELPHIA, PENNSYLVANIA, ASSIGNOR TO SCHUTTE & KOERTING COMPANY, OF PHILADELPHIA, PENNSYLVANIA, A CORPORATION OF PENNSYLVANIA

BAROMETRIC CONDENSER

Application filed July 21, 1931. Serial No. 552,110.

The principal object of the present invention is to provide a compact and self-contained barometric spray condenser which, by separate and internal water jet and spray actions, will remove not only condensed vapors but also noncondensable vapors, and to that and other ends hereinafter set forth or appearing, the invention, stated generally, comprises a barometric spray condenser having within its casing a water jet exhaust provided with its own tail pipe connection.

The invention also comprises the improvements to be presently described and finally claimed.

15 In the following description reference will be made to the accompanying drawing in which the single figure is a view principally in central section.

The apparatus is a jet condenser operating on the barometric principle, that is, with tail or leg pipe 34' long. The condensable vapors enter through the top opening (A) and are condensed by means of water sprays issuing from nozzles (C) arranged in a circle, spraying towards the center. The water enters through opening (G) and is distributed through ring space (B) to the spray nozzles (C). The removal of air and non-condensable gases is accomplished by means of converging water jets issuing from nozzles (L) inserted in nozzle case (H) receiving its water supply through opening (D). These jets discharge through a throat piece (M) and tail pipe (N) into the hotwell underneath. The sprayed water from nozzles (C) and the condensed vapors are collected in a tailpiece (E) surrounding the throat piece (M) and discharge separately through tailpipe (F) into the hotwell. To prevent the sprayed water from interfering with the solid jets issuing from nozzles (L) baffle (K) is provided, diverting the spray running down the sides of the nozzle case (H).

It may be remarked that the shell or casing (P) of the condenser is open top and bottom and tapers at its lower portion.

It will be obvious to those skilled in the art to which the invention relates that modifications may be made in details of construction and arrangement and matters of mere form

without departing from the spirit of the invention which is not limited to such matters or otherwise than the prior art and the appended claims may require.

I claim:

1. A barometric condenser having at its upper part means for injecting water to condense vapors and having a tail pipe for the injected water and condensed vapors, and provided internally with a water jet exhaust 55 for removing the non-condensable gases, and with a separate tail pipe connection depending from the casing for discharging the jet water and non-condensable gases substantially unmixed with the injected water 60 and condensed vapors.

2. A barometric condenser comprising a casing having a top opening for the reception of steam, a ring of spray nozzles arranged within the upper part and directed towards 70 the center of the casing, a ring of jet nozzles spaced from the wall of the casing and adapted to provide converging water jets, a throat piece projecting into the casing and adapted to receive the converging water jets and having a tail pipe connection, and a tail piece connection surrounding the throat piece with 75 annular space between.

3. A barometric condenser comprising an open ended casing of taper form at its lower 80 end, a throat piece projecting into the lower end of the casing with space between, means for introducing water into the upper part of the casing for discharge along with condensed vapors through said space and outside 85 of the throat piece, and provisions for introducing solid water jets into the throat piece for discharge through the throat piece along with non-condensable gases.

4. A barometric condenser comprising an open ended casing of taper form at its bottom part and provided at its upper part with a ring channel having a water receiving opening, nozzles communicating with said channel and arranged to discharge into the 95 casing, a nozzle case having a water inlet through the wall of the casing and arranged at an intermediate portion of the casing, jet nozzles communicating with the nozzle case, a tail pipe connection from the lower end of 100

the casing, and a throat piece having a tail pipe connection and extending through the first mentioned tail pipe connection and projecting into the casing into position for receiving water from the nozzles of the nozzle case.

5. A barometric condenser comprising an open ended casing of taper form at its bottom part and provided at its upper part with
10 a ring channel having a water receiving opening, nozzles communicating with said channel and arranged to discharge into the casing, a nozzle case having a water inlet through the wall of the casing and arranged
15 at an intermediate portion of the casing, jet nozzles communicating with the nozzle case, a tail pipe connection from the lower end of the casing, a throat piece having a tail pipe connection and extending through the first
20 mentioned tail pipe connection and projecting into the casing into position for receiving water from the nozzles of the nozzle case, and a baffle plate above the nozzles of the nozzle case.

25 6. A barometric condenser comprising a casing having an inlet opening for the reception of vapor to be condensed, means for injecting jets of water into said casing to condense said vapor, a tail piece for removing
30 said injected water and condensed vapors, a water jet exhauster within said casing for removing the non-condensable gases, and a tail pipe connection adapted to receive the jet of water from said exhauster and to dis-
35 charge said water and non-condensable gases separate from the injected water and condensed vapors.

7. In a barometric condenser the combination of a casing of taper form at its lower end
40 and open at its top for the reception of steam, means for introducing sprayed water into the upper part of this casing for condensing steam, and provisions within the casing for introducing solid converging water jets for
45 removing non-condensable gases.
